UNITED STATES PATENT OFFICE.

FRANZ SCHMIDT, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

HYDRAULIC TURBINE.

Application filed August 8, 1921. Serial No. 490,473.

To all whom it may concern:

Be it known that FRANZ SCHMIDT, a citizen of the United States, residing at Wauwatosa, in the county of Milwaukee and State of Wisconsin, has invented a certain new and useful Improvement in Hydraulic Turbines, of which the following is a specification.

This invention relates in general to improvements in the structure and operation of hydraulic apparatus, and relates more specifically to improvements in the construction of hydraulic turbines.

An object of the invention is to provide a hydraulic turbine which is simple in construction and efficient in operation. Another object of the invention is to provide an improved speed ring structure for hydraulic turbines which may be manufactured at minimum cost and which will effect most efficient delivery of the working fluid to the turbine.

It has heretofore been customary in various types of hydraulic turbines, to utilize a spiral conducting conduit for introducing the fluid to the turbine impeller. This inlet conduit is ordinarily formed to deliver the fluid inwardly toward the turbine axis. Within the spiral conduit, it is customary to provide a speed ring having stationary vanes which serve the dual function of properly guiding the entering fluid and of supporting upper turbine structure. In the speed rings of the prior art, it has been the universal custom to make all of the guide vanes of identical structure, that is of the same size and set at the same angle relatively to the turbine axis. It has also been customary to form the speed ring comprising the guide vanes and the adjacent conduit walls, as a single casting.

Due to the fact that the characteristics of the entering fluid are constantly changing as it advances along the spiral inlet conduit, it has been found that the prior structure embodying identical vanes, is relatively inefficient and that the vanes should be of different formation adjacent to different portions of the spiral inlet conduit. The present invention contemplates the provision of a speed ring having the vanes constructed with different characteristics so as

to produce maximum efficiency of admission of the fluid.

The prior constructions especially for large units, have also been found to be relatively expensive. With the present invention the speed ring side walls are formed of structural metal elements and sheet steel plates, whereby the cost of construction is not only reduced to a minimum, but a stronger structure results.

A clear conception of several embodiments of the invention and of the operation of apparatus constructed in accordance therewith, may be had by referring to the drawing accompanying and forming a part of this specification in which like reference characters designate the same or similar parts in the several views.

Fig. 1 is a transverse horizontal section through a hydraulic turbine installation embodying features of the invention.

Fig. 2 is a central vertical section through the hydraulic turbine installation disclosed in Fig. 1.

Fig. 3 is a fragmentary central vertical section through another type of installation embodying features of the invention.

The hydraulic turbine installation disclosed in Figs. 1 and 2, comprises in general a concrete setting 22 forming a horizontal inlet conduit 2 communicating tangentially with a spiral horizontal inlet conduit 3, a speed ring comprising an annular series of parallel vertical guide vanes 4, 5, 6, 7 located within the spiral inlet conduit 3, an annular series of adjustable flow controlling guide vanes 27 located within the speed ring, a Francis turbine impeller 8 disposed within the annulus formed by the adjustable guide vanes 27, and a draft tube 10 communicating with the turbine discharge.

While the conduits 2, 3 have been specifically illustrated as formed by the concrete setting 22, it will be understood that these conduits may be enclosed by a casting or by a sheet metal casing instead of the concrete. Due to the fact that fluid is discharged from the spiral inlet conduit 3 at all points about the turbine axis, and in order to provide a relatively uniform supply of fluid to all portions of the turbine without creat-

ing pockets or spaces which are not filled with fluid, the cross-sectional area of the conduit 3 gradually diminishes in the direction of flow of the fluid through the conduit. The 5 delivery of fluid from the spiral inlet conduit 3, inwardly toward the turbine axis may be either horizontal as shown, or vertical, or inclined at an angle to the horizontal.

The speed ring illustrated in Figs. 1 and 2 10 comprises an annular series of stationary guide vanes 4, 5, 6, 7 which span the discharge opening leading from the spiral casing 3. These guide vanes which under certain conditions act as tension members and 15 under other conditions serve as compression members, may be formed of any suitable material capable of withstanding the forces to which they are subjected, and may in some instances be made of cast iron or steel, 20 whereas in other cases it may be desirable to form them of sheet metal. The vanes 6 adjacent to the portion of the inlet conduit 3 having greatest cross-sectional area, are set at a different angle relatively to the turbine 25 axis than are the other vanes of the speed ring, the difference in angle being indicated in Fig. 1 wherein the vanes shown in dot and dash have the same angle as the remaining vanes while the vanes illustrated in 30 full lines are constructed in accordance with the present invention. From the disclosure in Fig. 1 it will also be apparent that the vanes 6 adjacent to the portion of the conduit 3 having greatest cross-sectional area, 35 are wider than the succeeding set of guide vanes 5, the width being measured in the direction of flow of the fluid. The vanes 5 are also wider measured in the direction of flow of the fluid, than the vanes 7 of the next set, 40 which are likewise wider than the vanes 4 of the next set. This variation in the characteristics, namely, width and angularity of the vanes produces a speed ring adapted to effectively conduct the fluid from the spiral inlet conduit 3 to the turbine impeller 8 and to 45 insure uniform delivery of fluid to all portions of the turbine impeller. The variation in width also permits reduction of the overall dimension of the casing forming the spiral conduit, to a minimum. It will be obvious 50 that the specific structure illustrated may be applicable to only a limited set of conditions and that the specific design must necessarily be changed to meet variations in these 55 conditions.

The upper and lower walls of the speed ring are formed of sheet metal plane plates 11, 12 respectively, which are attached to the 60 ends of the vanes 4, 5, 6, 7 in any convenient manner as by welding, riveting or with the aid of screws. The plates 11, 12 are preferably made of commercial sheet steel and in several sections. The upper plate 11 is secured to the adjacent turbine structure by 65 means of an annular channel bar 28 and an

angle bar 30, these bars being fastened to the plate in any convenient manner as by welding or riveting, and being interlocked with the concrete 22. The lower plate 12 is likewise attached to the adjacent turbine structure by means of an annular channel bar 14 and an annular angle bar 29 attached to the plate 12. The channel and angle bars 14, 28, 29, 30 are preferably made of standard structural material and effectively serve 70 to retain the plates 11, 12 and the vanes 4, 5, 6, 7 in proper position. The speed ring guide vanes besides serving to properly conduct the fluid entering the turbine, also serve as struts for supporting upper turbine structure resting upon the upper plate 11 and as tension members for preventing spreading of the plates 11, 12.

The flow controlling guide vanes 27 are 75 adjustably supported in the lower and upper turbine casings 16, 20 respectively, by means of adjusting pivots 15 whereby the vanes 27 may be adjusted to vary the degree of whirl of the entering fluid and also to increase or diminish the volume of fluid entering the impeller. The adjustment of the guide vanes 27 is ordinarily effected by 80 means of a speed governor acting through a suitable servo-motor. The lower turbine casing 16 is secured to the concrete setting 95 22 directly above the draft tube 10, while the upper turbine casing 20 is secured to the upper speed ring plate 11 and the channel bar 28.

The turbine impeller comprises an outer 100 annular rim 17 cooperating with the lower turbine casing 16, a plurality of vanes secured to the rim 17 and to a central hub, and a main shaft 9 attached to the hub and supported in a suitable bearing 13 secured 105 to the upper casing 20.

The hydraulic turbine installation disclosed in Fig. 3, comprises a setting and inlet conduits similar to those of Figs. 1 and 2, but differs from the installation previously described, in the construction of the speed ring and of the turbine. In the installation illustrated in Fig. 3, the speed ring comprises an annular series of stationary struts or tension members 18 each of 110 which has upper and lower ends extending through openings in the upper and lower plates 25, 26 respectively, these ends being secured to the plates by nuts or other suitable fastening devices. The struts or tension 115 members 18 as disclosed, have circular cross-section but they may be shaped as vanes and are constructed of any suitable material capable of withstanding the applied forces. Each of the plates 25, 26 are preferably 120 formed annular either in one piece or of several sections, the plates being preferably constructed of commercial sheet steel. The upper plate 25 is secured to the adjacent 125 turbine structure by means of an annular 130

channel bar 28 and an angle bar 30, these bars being fastened to the plate in any convenient manner and being interlocked with the concrete which forms the turbine setting. The lower plate 26 is likewise attached to the concrete setting by means of an annular channel bar 14 and an annular angle bar 29 attached to the plate 26 and embedded in the adjacent concrete. The 10 channel and angle bars 14, 28, 29 and 30, are preferably made of commercial structural material and effectively serve to retain the plates 25, 26 in proper position.

As in the installation previously described, 15 the flow controlling guide vanes 27 are adjustably supported in the lower and upper stationary turbine casings 31, 19 respectively, by means of adjusting pivots 15 whereby the vanes 27 may be adjusted to vary 20 the degree of whirl of the entering fluid and also to increase or diminish the volume of fluid entering the turbine. The lower turbine casing 31 is secured to the concrete turbine setting directly above the draft tube, 25 while the upper turbine casing 19 is secured to the upper speed ring plate 25. The turbine impeller 21 is of the axial flow type and is attached to the lower extremity of the main shaft 24 which is supported in a 30 bearing in the upper turbine casing 19. The turbine impeller 21 receives fluid which passes the adjustable guide vanes 27, from a vane-free transition space 23 which is bounded by the upper and lower turbine 35 casings 19, 31.

During normal operation of the installation illustrated in Figs. 1 and 2, the fluid is admitted to the turbine through the conduits 2, 3, past the stationary speed ring 40 vanes 4, 5, 6, 7 and past the adjustable guide vanes 27. After delivering energy to the impeller 8, the fluid is delivered from the turbine through the draft tube 10. In the installation disclosed in Fig. 3, the fluid is 45 admitted from the conduit 3 through the speed ring and past the adjustable guide vanes 27 to the vane-free transition space 23 from whence the fluid passes through the impeller 21 to the draft tube. The control 50 of the speed and of the quantity of fluid passing through the impeller is effected by adjustment of the movable guide vanes 27.

It will be obvious that by constructing 55 the stationary inlet guide vanes 4, 5, 6, 7 of the speed ring illustrated in Figs. 1 and 2, as disclosed, the fluid will be admitted to the turbine impeller at the most efficient angle and uniform delivery of fluid to all portions of the impeller will be insured. 60 The construction of the speed ring with individual guide vanes or members and annular sheet metal side plates secured to the concrete setting by means of annular channel and angle bars, reduces the cost of construction to a minimum and permits con-

struction of the speed ring at the hydraulic site. This structure is especially advantageous in large units wherein it eliminates necessity of employing large castings, the transportation and installation of which is 70 exceedingly burdensome. The speed ring structure, besides being inexpensive, possesses maximum strength and permits selection of desirable materials in its construction.

It should be understood that it is not desired to limit the invention to the exact 75 details of construction and operation herein shown and described, for obvious modifications may occur to persons skilled in the art.

It is claimed and desired to secure by Letters Patent:

1. In a hydraulic machine, a rotor having an axis, a speed ring comprising an annular series of guide vanes formed to conduct fluid toward said axis from all sides, at least one of said vanes having a characteristic which is different from corresponding characteristics of other of said vanes, and means forming a spiral conduit 85 communicating with said vanes and completely surrounding said axis.

2. In a hydraulic machine, a rotor having an axis, means for controlling the flow of fluid to said rotor, a speed ring comprising an annular series of vanes surrounding said flow control means and formed to conduct fluid toward said axis from all sides, at least one of said vanes having a characteristic which is different from corresponding characteristics of other of said vanes, and means forming a spiral conduit 95 communicating with said vanes and completely surrounding said axis.

3. In a hydraulic machine, a rotor having an axis, a speed ring comprising an annular series of guide vanes formed to conduct fluid toward said axis from all sides, the angularity of at least one of said vanes relatively to said axis being different from that of another, and means forming a spiral conduit communicating with said vanes and completely surrounding said axis.

4. In a hydraulic machine, a rotor having an axis, means for controlling the flow of fluid to said rotor, a speed ring comprising an annular series of vanes surrounding said flow control means and formed to conduct fluid toward said axis from all sides, the angularity of at least one of said vanes relatively to said axis being different from that of another, and means forming a spiral conduit communicating with said vanes and completely surrounding said axis.

5. In a hydraulic machine, a rotor having an axis, a speed ring comprising an annular series of guide vanes extending parallel to said axis and formed to conduct fluid toward said axis from all sides, at least one of said vanes having a charac-

- teristic which is different from corresponding characteristics of other of said vanes, and means forming a spiral conduit communicating with said vanes and completely surrounding said speed ring. 5 portion of said conduit having greatest 65 cross-sectional area.
6. In a hydraulic turbine, means forming a spiral fluid conducting conduit, and an annular series of guide vanes within said conduit, the angularity relatively to the turbine axis of the vanes adjacent the portion of said conduit having smallest cross-sectional area being less than that of said vanes adjacent to the portion of said conduit having greatest cross-sectional area. 10 12. In a hydraulic turbine, means forming a conduit for conducting fluid transversely of the turbine axis, and a series of 70 guide vanes in said conduit, the angularity of at least one of said vanes relatively to said axis being different from that of another and at least one of said vanes being narrower than another measured in the direction of flow of fluid. 75
7. In a hydraulic machine, a rotor having an axis, a speed ring comprising an annular series of guide vanes formed to conduct fluid toward said axis from all sides, at least one of said vanes being narrower than another measured in the direction of 20 flow of fluid, and means forming a spiral conduit communicating with said vanes and completely surrounding said axis. 15 13. In a hydraulic turbine, means forming an annular fluid conducting conduit, and an annular series of parallel guide vanes spanning said conduit, the angularity of at least one of said vanes relatively to the axis 80 of annularity of said conduit being different from that of another and at least one of said vanes being narrow than another measured in the direction of flow of fluid. 85
8. In a hydraulic machine, a rotor having an axis, means for controlling the flow of fluid to said rotor, a speed ring comprising an annular series of vanes surrounding said flow control means and formed to conduct fluid toward said axis from all sides. 25 14. In a hydraulic turbine, means forming a spiral fluid conducting conduit, and an annular series of guide vanes within said conduit, the angularity of at least one of said vanes relatively to the axis of spirality of said conduit being different from that of another and said vanes adjacent to the portion of said conduit of smallest cross-sectional area being narrower measured in the direction of flow of fluid than the vanes 90 adjacent to the portion of said conduit of greatest cross-sectional area. 95
9. In a hydraulic machine, a rotor having an axis, a speed ring comprising an annular series of vanes formed to conduct fluid toward said axis from all sides, at least one of said vanes being narrower than another measured in the direction of flow of fluid, and means forming a spiral conduit communicating with said vanes and completely surrounding said axis. 30 15. In a hydraulic turbine, means for controlling the delivery of fluid to the turbine, and a speed ring surrounding said controlling means, said speed ring comprising an 100 annular series of vanes some of which are wider than others measured in the direction of flow of fluid. 105
10. In a hydraulic machine, a rotor having an axis, a speed ring comprising an annular series of guide vanes formed to conduct fluid toward said axis from all sides, at least one of said vanes having a characteristic which is different from corresponding characteristics of other of said vanes, means forming a spiral conduit communicating laterally with said vanes from 35 all sides of said axis, and a flow decelerator communicating with said rotor in line with said axis. 110 16. In a hydraulic turbine, means for controlling the flow of fluid to the turbine, and a speed ring surrounding said controlling means, said speed ring comprising an annular series of vanes the angularity of some of which relatively to the turbine axis is different from that of others. 115
11. In a hydraulic turbine, means forming a spiral fluid conducting conduit, and an annular series of vanes within said conduit, the vanes adjacent to the portion of said conduit having smallest cross-sectional area being narrower measured in the direction of flow of fluid than said vanes adjacent to the 40 120 17. In a hydraulic turbine, means for controlling the flow of fluid to the turbine, and a speed ring surrounding said controlling means, said speed ring comprising an annular series of guide vanes the angularity of some of which relatively to the turbine axis is different from that of others and the width of some of which is different from that of others measured in the direction of flow of fluid. 125
18. In a hydraulic turbine, a speed ring comprising upper and lower plates, structural metal members secured to said plates and to adjacent turbine structure, and a series of members connecting said plates. 125
19. In a hydraulic turbine, a speed ring comprising upper and lower sheet metal plates, means for attaching said plates to the

adjacent turbine structure, and a series of guide vanes connecting said sheet metal plates.

20. In a hydraulic turbine, a speed ring comprising upper and lower sheet metal plates, structural metal members secured to said plates and to the adjacent turbine structure, and a series of members secured to and connecting said plates.

21. In a hydraulic turbine, a speed ring comprising annular plane sheet metal upper and lower plates, structural metal members secured to said plates and to the adjacent turbine structure, and an annular series of 15 guide vanes attached to and directly connecting said plates.

22. In a hydraulic turbine, a speed ring comprising an annular sheet metal plate, structural metal members secured to said 20 plate and to the adjacent turbine structure, and guide vanes secured to said plate and spanning the turbine inlet conduit.

23. In a hydraulic turbine, a speed ring comprising an annular sheet metal top plate,

structural metal members secured to said 25 plate and to upper turbine structure, and a series of members depending from said plate and resting upon lower turbine structure.

24. In a hydraulic turbine, a speed ring comprising an annular sheet metal top plate 30 adapted to support upper turbine structure, and an annular series of members depending from said plate and resting upon lower turbine structure.

25. In a hydraulic machine, a rotor having an axis, a speed ring comprising an annular series of vanes formed to conduct fluid toward said axis from all sides, at least one of said vanes having a characteristic which is different from corresponding 40 characteristics of other of said vanes, means for admitting fluid to said speed ring from all sides of said axis, and a flow decelerator communicating with said rotor in line with said axis.

In testimony whereof, the signature of the inventor is affixed hereto.

FRANZ SCHMIDT.
